UNITED STATES PATENT OFFICE

HAROLD C. HOYT, OF THOMASTON, CONNECTICUT

LOUD SPEAKER

Application filed July 3, 1930. Serial No. 465,567.

This invention relates to loud speakers of the dynamic type for amplifying electromagnetic vibrations received from phonographs, radios, talking picture films, and other sources, and more particularly to an improved diaphragm for such a loud speaker.

One object of the invention is to provide a metallic loud speaker diaphragm of the above nature which will be capable of amplifying at high volume both high and low frequency vibrations.

A further object is to provide a diaphragm of the above nature in which undesired metallic sounds produced by the natural period of the diaphragm are eliminated.

A further object is to provide a device of the above nature which will be simple in construction, inexpensive to manufacture, easy to assemble and manipulate, compact, ornamental in appearance, and very efficient and durable in use.

With these and other objects in view there has been illustrated on the accompanying drawing one form in which the invention may be conveniently embodied in practice.

In the drawing:

Fig. 1 represents a front view of a dynamic loud speaker and diaphragm embodying the invention.

Fig. 2 is a transverse sectional view of the same, taken along the line 2—2 of Fig. 1 looking in the direction of the arrows.

Fig. 3 is a sectional view on an enlarged scale of one of the tripod arms of the loud speaker, taken along the line 3—3 of Fig. 1, looking in the direction of the arrows.

Fig. 4 is a fragmentary sectional view on an enlarged scale of the outer portion of the diaphragm and frame, taken along the line 4—4 of Fig. 1, looking in the direction of the arrows.

In previous metal diaphragms for dynamic loud speakers considerable trouble has been experienced due to the undesired metallic sounds produced by the natural period of vibration of the diaphragm itself. One method of avoiding these objectionable sounds has been to stretch the metal diaphragm so that said natural period is of so high a pitch that the sounds produced there-

by will be inaudible. This type of device, however, is very objectionable because owing to its highly stretched condition it will not properly respond to the low frequency vibrations. Hence, while high notes are radiated in a satisfactory manner, sounds of low pitch are radiated imperfectly.

By means of the present invention, the above and other disadvantages have been overcome, and an electromagnetic diaphragm for a dynamic loud speaker has been produced which will be free from undesirable sounds due to its natural period of vibration, and at the same time will reproduce perfectly sounds of both high and low frequency over the entire audible range. This has been accomplished by stretching the metal of the diaphragm to a point just under the natural period of vibration, and absorbing the sounds due to said natural period by means of a ring of packing material located under the outer periphery of the diaphragm, at which point it has been found that such undesired sounds due to the natural period of the metal are practically all radiated.

To complete the manufacture of the diaphragm which would otherwise be too elastic and would cause an uneven response to the electromagnetic impulses of the driving coil and produce rattling and blurred and harsh, roaring sounds at low frequencies under strong power, the present invention contemplates the attachment of a plurality of thin damping strips to the inner surface of the metal diaphragm. The strips are preferably tangentially arranged with their inner edges overlapping, leaving an unsupported area at the central portion of the diaphragm. This stiffening of the outer portion of the diaphragm will permit it to radiate faithfully the low frequency vibrations while the unstiffened central area thereof will be free to radiate the high frequency vibrations.

By means of a diaphragm made in accordance with the present invention, an accurate response will be obtained to vibrations of all frequencies from 30,000 cycles per second at the high end of the scale down to any desired point on the low end of the scale, as determined by the size of the diaphragm, the

weight of the driving coil and the thickness of the metal sheet.

Referring now to the drawing in which like reference numerals denote corresponding parts throughout the several views, the numeral 10 indicates a thin sheet metal diaphragm, preferably circular in shape. The diaphragm is preferably composed of aluminum alloy, such as duralumin or hard rolled 10 aluminum.

The diaphragm sheet 10 is first laid with its outer edge located between a pair of circular clamping bands 11 and 12, preferably 15 constructed of the same metal as the diaphragm 10, so as to avoid uneven expansion effects due to changes in temperature. The clamping bands 11 and 12, together with the diaphragm 10 held tightly therebetween, are then placed upon a ring shaped frame 13, 20 substantially twice as large in diameter as the bands 11 and 12. The bands 11 and 12 are next bolted to said frame 13 by means of a plurality of studs 14, which desirably pass through every other one of a series of 25 holes 15, spaced equally about the circumference of the frame 13.

In order to more securely clamp the bands 11 and 12 about the periphery of the diaphragm 10, additional screw bolts 16 are 30 employed and are passed through the other holes 15, alternating with the studs 14. The frame 13 and diaphragm 10 are adapted to be supported as a unit in spaced relation from the exciting coil, not shown, by three 35 inclined tripod legs 17, having transverse feet sections 18 adapted to be attached to the frame 13 as by screws 19. The tripod legs 17 are secured at their inner ends to a shouldered 40 ring 20 which is shaped to fit the base of said exciting field coil, not shown.

After the diaphragm unit has been secured to the tripod legs 17, a damping ring 21 of any suitable flexible packing material, such as felt or cellucotton, is forced between the 45 diaphragm 10 and the inner portions of the annular frame 13. This packing material serves to absorb all metallic sounds or harmonies due to vibrations in synchronism with the natural period of the sheet metal.

50 The next step in the production of the improved loud speaker is to stiffen the outer portion of the diaphragm. For this purpose, a plurality of thin strips 22 of light material, such as balsa wood, are positioned in 55 the tangential arrangement shown in Fig. 1, being so placed as to form an unstiffened square central area 23 at the center of the diaphragm 10. The strips 22 are preferably attached to the diaphragm by rubber cement 60 and also by a row of stitching 24 of silk thread sewed through the diaphragm, and consolidated therewith by means of a cement containing a phenolic condensation product. 65 The strips 22 permit the diaphragm to accurately radiate the low frequency vibrations

at the outer portion of said diaphragm. The central unstiffened portion of the diaphragm being fairly light and flexible and not requiring much movement, will accurately radiate all the high frequency vibrations. 70

In order to absorb any undesired resonance and metallic vibrations which might originate therein, each of said tripod legs 17 is made channel-shaped in cross-section and has its base 25 and inclined sides 26 covered 75 with a felt strip 27 adapted to be held in place by a wedge-shaped strip of wood 28 secured to said base 25, as by screws 29.

It has been found that three of the tripod legs 17 are sufficient to hold the dynamic diaphragm unit in rigid position, but it will be understood that any other number of legs may be employed within the spirit of the invention. The covering on the tripod legs 17 serves to prevent any resonance and metallic sounds transmitted thereto by the frame work etc. 80

While there has been disclosed in this specification one form in which the invention may be embodied, it is to be understood that this form is shown for the purpose of illustration only, and that the invention is not to be limited to the specific disclosure but may be modified and embodied in various other forms without departing from its spirit. In short, 85 the invention includes all the modifications and embodiments coming within the scope of the following claims. 90

Having thus fully described the invention what is claimed as new and for which it is 100 desired to secure Letters Patent is:

1. In a dynamic loudspeaker, a metal diaphragm, a frame surrounding said diaphragm, and a plurality of strips of light weight attached to said diaphragm for damping the vibration of the outer part of said diaphragm to prevent radiation of undesired rattling and roaring sounds of low frequencies under strong power, said diaphragm having an unsupported central section for 110 radiating sounds of low pitch, said strips being arranged in substantially radial overlapping positions tangent to said central section. 105

2. In a dynamic loudspeaker, a metal diaphragm, a frame surrounding said diaphragm, and a plurality of strips of balsa wood attached to said diaphragm for damping the vibration of the outer part of said diaphragm to prevent radiation of undesired rattling and roaring sounds of low frequencies under strong power, said diaphragm having an unsupported central section adapted to radiate low pitch sound vibrations, said strips being arranged substantially radially 120 about said central section. 115

3. In a dynamic loudspeaker, a stretched metal diaphragm, a frame surrounding said diaphragm, and a plurality of strips attached 125 to said diaphragm for damping the vibra- 130

tion of the outer part of said diaphragm to prevent radiation of undesired rattling and roaring sounds of low frequencies under strong power, said diaphragm having an unsupported circular central section for radiating low pitch sound vibrations, said strips being located with their inner ends tangent to said unsupported section.

4. In a dynamic loudspeaker, a stretched diaphragm having an audible natural period of vibration, a frame surrounding said diaphragm, a plurality of strips for damping the vibration of the outer part of said diaphragm to prevent radiation of undesired blasts, said diaphragm having an unsupported circular central section for radiating low pitch sound vibrations, said strips being located with their inner ends tangent to said circular section.

20 5. In a dynamic loudspeaker, a frame for supporting the periphery of a thin metallic diaphragm, a ring for supporting a driving coil, a plurality of inclined legs for connecting said frame with said ring, said legs being covered with sound absorbing material.

6. In a dynamic loudspeaker, a frame for supporting the periphery of a thin metallic diaphragm, a ring for supporting a driving coil, a plurality of inclined legs for connecting said frame with said ring, each of said legs being channel-shaped and having a wedge member fitted within the open side of said channel for sound-absorbing purposes.

7. In a dynamic loudspeaker, a frame for supporting the periphery of a thin metallic diaphragm, a ring for supporting a driving coil, a plurality of inclined legs for connecting said frame with said ring, each of said legs being channel-shaped and having a wedge member fitted within the open side of said channel, and a strip of felt embracing said channel and being held in place by said wedge member.

In testimony whereof, I have affixed my
45 signature to this specification.

HAROLD C. HOYT.
